(57) **CLAIM**

The ornamental design for a bag for packaging, as shown and described.

DESCRIPTION

The patent or application file contains at least one drawing executed in color. Copies of this patent or patent application publication with color drawing(s) will be provided by the Office upon request and payment of the necessary fee.

1. Bag for packaging

1.1 : Perspective

1.2 : Front

1.3 : Back

1.4 : Top

1.5 : Bottom

1.6 : Right side view

1.7 : Left side view

1.8 : Reference perspective view

The portion illustrated with solid lines is the portion for which design registration is sought; the dashed lines shown in the drawing form no part of the claimed design; the two parallel long dashed lines shown in the perspective view and the top view illustrate perforations (tear slits) to open the bag and form part of the claimed design; the thin straight lines shown in the perspective view are used to specify the three-dimensional shape of the article; the reproduction 1.8 is a reference view and protection is not claimed for the design shown therein.
